GAME BOARD

Jack N. Thomas, East Point, Ga.
(Star Rte., Reidsville, Ga. 30453)

Filed May 28, 1965, Ser. No. 85,494

Term of patent 3½ years

(Cl. D34—5)

The dominant features of my design reside in the portions shown in full lines.

I claim:

The ornamental design for a game board, as shown and described.
